UNITED STATES PATENT OFFICE.

MARY CHASE BARON, OF HAMDEN MEADOWS, RHODE ISLAND.

DESIGN FOR A MOISTURE-TANK FOR A BROODER-HEATER.

57,572.

Specification for Design.

Patented Apr. 26, 1921.

Application filed August 26, 1920. Serial No. 406,238. Term of patent 14 years.

To all whom it may concern:

Be it known that I, MARY CHASE BARON, a citizen of the United States, residing at Hampden Meadows, county of Bristol, and State of Rhode Island, have invented a new, original, and ornamental Design for a Moisture-Tank for a Brooder-Heater, of which the following is a specification, refer-

ence being had to the accompanying drawing, forming part thereof.

The figure is a perspective view of a brooder heater.

I claim—

The ornamental design for a moisture tank for a brooder heater, as shown.

MARY CHASE BARON.
